UNITED STATES PATENT OFFICE

LESLIE A. RAWSON, OF LOS ANGELES, CALIFORNIA, ASSIGNOR TO EMSCO DERRICK & EQUIPMENT COMPANY, OF LOS ANGELES, CALIFORNIA, A CORPORATION OF CALIFORNIA

JACK CLIP

Application filed July 20, 1929. Serial No. 379,806.

My invention relates to a derrick construction and relates particularly to a novel corner construction for the base of a derrick.

A derrick is used in the well drilling industry for handling the apparatus used in drilling the well. The derrick structure and the drilling apparatus are supported by base corners of the derrick which are thereby subjected to considerable stress as the weight which they support amounts to many tons. Because of the great weight which is supported, it is quite a common occurrence for the foundation of one or more corners of the derrick to settle and throw the derrick out of vertical alignment. This makes it necessary to jack up the low corner and place shims thereunder in order to realign the derrick.

It is an object of my invention to provide a convenient means of attaching a lifting jack to the corner of the derrick so as to allow the corner to be lifted.

It is another object of my invention to provide a device for use on the base corners of a derrick which will form a stronger and more rigid corner than the corners now used.

It is customary to use a plurality of parts to secure the various derrick members, such as derrick legs, base channels, reinforcing members, etc., and since the derrick members meet at various angles and the base corner parts must be of large size in order to withstand the stresses to which they are subjected, this makes a very complicated construction.

It is a further object of my invention to provide a base corner which will be of simple construction and which will provide means for readily securing the various derrick members thereto.

The construction of a derrick is such that the sides of the base channels are vertical while the derrick legs are inclined so as to converge toward the top of the derrick. In order to better fit the derrick members, it is desirable that the portions of the base corners secured to the base channels be constructed vertically and the portions secured to the derrick legs be inclined parallel to the derrick legs. In the base corners of my inven-

tion I have made it an object to provide for this construction.

It is also an object of my invention to provide a means of easily attaching the derrick legs to the base corners so as to readily support the weight thereof.

Further objects of my invention will appear hereinafter.

In the accompanying drawings, in which I have shown a device of my invention:

Fig. 1 is a view showing the appearance of my device.

Fig. 2 is a vertical view from above a derrick showing the device in position on the derrick.

Fig. 3 is a sectional view taken on the line 3-3 of Fig. 2.

Fig. 4 is a side view showing the arrangement of the parts.

Referring to the drawings, the base of a derrick is composed of vertical-sided base channels 11 which form a rectangle and which are reinforced by reinforcing channels 12. The base channels 11 are attached at each corner of the derrick to a base corner 14 as are also an inclined derrick leg 15 and a diagonal reinforcing member 16, the reinforcing member 16 being connected to diagonally opposite corners of the derrick so as to brace the derrick.

The base corner 14 of my invention consists of a horizontal wall 17 which has a lower face 18 supported on an upper face 19 of a foundation block 20 and is secured thereto by suitable means such as bolts 21. Extending upwardly from the horizontal wall 17 and integral therewith are two intersecting upwardly-extending walls 23 which form a right angle having an apex 24. The inside surfaces of the walls 23 adjacent the apex 24 are constructed parallel to the flanges of the inclined derrick leg 15 so as to form suitable attaching surfaces for the derrick leg 15 which is secured thereto by bolts 25. The extremities of the walls 23 farthest from the apex 24 are constructed vertically and form attaching surfaces for attaching the vertical sides of the base channels 11 which are secured thereto by bolts 28. I thus provide in

my base corner an inclined surface for attaching the inclined derrick leg 15 and a vertical surface for attaching the vertical-sided base channels 11.

- 5 On the external faces of the walls 23, between the apex 24 and the point of attachment of the base channels 11, are projections 30 which provide projecting faces 31 that are perpendicular to the axis of the diagonal 10 reinforcing member 16. Formed in the projections 30 are horizontal openings 32, in one of which is positioned a threaded end 33 of the reinforcing member 16. A tightening nut 34 on the threaded end 33 of the reinforcing 15 member 16 is tightened against the faces 31 of one of the projections 30, which face forms a thrust surface therefor. Attaching means is thus provided for attaching the diagonal reinforcing member 16 to my base corner 14.
- 20 As best shown in Fig. 3, I provide, in the upper inclined face of the horizontal wall 17 and between the walls 23, a supporting surface or concavity 36 for supporting a convex head 37 of an adjusting jack 38 which jack is 25 secured to the lower end of the derrick leg 15 and provides a means of adjusting the vertical position thereof. The concavity 36 thus forms a support for the derrick leg 15.

Extending from the apex 24 is a horizontal 30 lifting member or lifting arm 40 which is formed integrally with the walls 23. The arm 40 is provided with integrally-formed upper and lower reinforcing webs 41 and 42 and with a lower horizontal face 43 which 35 provides a surface for contacting the head of a lifting jack which may be placed thereunder as shown by the dotted lines 44 in Fig. 3. By forming the arm 40 integrally with the base corner 14 and providing it with reinforcing webs 41 and 42, I provide it with 40 sufficient strength to support the weight of the derrick leg 15.

The base corner of my invention thus 45 forms a stronger, more rigid and more accessible corner than the type now used and provides a means for readily attaching a lifting jack thereto.

I claim as my invention:

- 50 1. In a derrick, the combination of: an integrally-formed base corner; a lifting member integral with said base corner; a derrick leg attached to and supported by said base corner; and a base channel attached to said base corner.

55 2. In a derrick, the combination of: an integrally-formed base corner; a lifting member integral with said base corner; a derrick leg attached to and supported by said base corner; a base channel attached to said base corner; and a reinforcing member attached to said base corner.

60 3. In a derrick, the combination of: an integrally-formed base corner; a lifting arm 65 extending from said base corner and integral

therewith; a derrick leg attached to and supported by said base corner; and a base channel attached to said base corner.

4. In a derrick, the combination of: an integrally-formed base corner; a lifting arm 70 extending from said base corner and integral therewith; a derrick leg attached to and supported by said base corner; a base channel attached to said base corner; and a reinforcing member attached to said base corner to 75 between the attachment of said base corner to said derrick leg and the attachment of said base corner to said base channel.

5. As an article of manufacture, an integrally-formed base corner for a derrick, 80 comprising: a lifting member integral with said base corner; an attaching surface on said base corner adapted to fit a surface of a derrick leg; and an attaching surface on said base corner adapted to fit a surface of a base 85 channel.

6. As an article of manufacture, an integrally-formed base corner for a derrick, comprising: a lifting arm extending from and integral with said base corner; an attaching 90 surface on said base corner adapted to fit a surface of a derrick leg; and an attaching surface on said base corner adapted to fit a surface of a base channel.

7. As an article of manufacture, an integrally-formed base corner for a derrick, comprising: a lifting member integral with said base corner; an inclined attaching surface on said base corner adapted to fit an inclined surface of a derrick leg; and an attaching surface on said base corner adapted to fit a surface of a base channel.

8. As an article of manufacture, an integrally-formed base corner for a derrick, comprising: a lifting member integral with said base corner; an attaching surface on said base corner adapted to fit a surface of a derrick leg; and a vertical attaching surface on said base corner adapted to fit a vertical surface of a base channel.

9. As an article of manufacture, an integrally-formed base corner for a derrick, comprising: a lifting member integral with said base corner; an attaching surface on said base corner adapted to fit a surface of a derrick leg; an attaching surface on said base corner adapted to fit a surface of a base channel; and an attaching means on said base corner adapted for attaching a reinforcing member.

10. As an article of manufacture, an integrally-formed base corner for a derrick, comprising: a lifting member integral with said base corner; an attaching surface on said base corner adapted to fit a surface of a derrick leg; an attaching surface on said base corner adapted to fit a surface of a base channel; and a supporting surface on said base corner for supporting said derrick leg.

11. As an article of manufacture, an in-

tegrally-formed base corner for a derrick, comprising: a horizontal wall; an upper surface on said wall adapted to support a derrick leg; an upwardly-extending wall above said horizontal wall and integral therewith; an attaching surface on said upwardly-extending wall adapted to fit a surface of said derrick leg; an attaching surface on said upwardly-extending wall adapted to fit a surface of a base channel; and a lifting member on said upwardly-extending wall and integral therewith.

12. As an article of manufacture, an integrally-formed base corner for a derrick, comprising: a horizontal wall; an upper surface on said wall adapted to support a derrick leg; an upwardly-extending wall above said horizontal wall and integral therewith; an attaching surface on said upwardly-extending wall adapted to fit a surface of said derrick leg; an attaching surface on said upwardly-extending wall adapted to fit a surface of a base channel; and a lifting arm extending from said upwardly-extending wall and integral therewith.

13. As an article of manufacture, an integrally-formed base corner for a derrick, comprising: a horizontal wall; an upper surface on said wall adapted to support a derrick leg; upwardly-extending mutually-angled walls above said horizontal wall and integral therewith; an attaching surface on said upwardly-extending walls adapted to fit a surface of said derrick leg; an attaching surface on said upwardly-extending walls adapted to fit a surface of a base channel; and a lifting member on said upwardly-extending walls and integral therewith.

14. As an article of manufacture, an integrally-formed base corner, comprising: a horizontal wall; a groove in the upper surface of said wall adapted to receive a derrick leg; an upper surface on said wall adapted to support an auxiliary derrick leg; upwardly-extending mutually-angled walls above said horizontal wall and integral therewith; an attaching surface on said upwardly-extending walls adapted to fit a surface of said derrick leg; an attaching surface on said upwardly-extending walls adapted to fit a surface of a base channel; and a lifting member on said upwardly-extending walls and integral therewith.

15. In a derrick, the combination of: an integrally-formed base corner; a lifting member integral with said base corner; a derrick leg attached to and supported by said base corner; a base channel attached to said base corner; an adjustable elevating means supported by said base corner; and an auxiliary derrick leg supported by said elevating means.

16. In a derrick, the combination of: an integrally-formed base corner; a lifting member integral with said base corner; a derrick leg attached to and supported by said base

corner; a base channel attached to said base corner; a reinforcing member attached to said base corner between the attachment of said base corner to said derrick leg and the attachment of said base corner to said base channel; an adjustable elevating means supported by said base corner; and an auxiliary derrick leg supported by said elevating means.

In testimony whereof, I have hereunto set my hand at Los Angeles, California, this 8th day of July, 1929.
